Letters Patent No 1861-Dated Nov. 24, 1868
Design for a Carpet Pattern.

The schedule referred to in these Letters Patent and making part of the same,
To all whom it may concern:

Be it known that I, Henry G. Thompson, of the City, County and State of New York, have invented or produced a new and original design for a Pattern to be wrought into Three-ply Ingrain and other carpeting, in colors similar to those painted on the drawings accompanying this specification, or in other colors substituted in the place of those painted on the drawings herewith; and I do hereby declare that the drawings accompanying this specification, do give and
